UNITED STATES PATENT OFFICE

2,099,447

POLICE WEAPON

Frank A. Matsuyama, San Francisco, Calif.

Application August 20, 1937, Serial No. 160,030

4 Claims. (Cl. 273—84)

My invention relates to police weapons, and more particularly to a new and useful club for the use of police and other peace officers in maintaining law and order.

5 Among the objects of my invention are: To provide a hand-held weapon projecting only a short distance each side of the hand; to provide a hand-held weapon having finger ridges to prevent the weapon from being forced out of the hand, and having short ends projecting both sides of the hand and terminating in rounded striking ends; to provide a police weapon of small size which has provision thereon to minimize the chance of having the weapon wrested from 10 the hand of the user during action; and to provide a police weapon which is useful for police officers trained in "Yawara", a Japanese system of defense and offense.

Other objects of my invention will be apparent 20 or will be specifically pointed out in the description forming a part of this specification, but I do not limit myself to the embodiment of the invention herein described, as various forms may be adopted within the scope of the claims.

25 The figure is a side view of one preferred form of my invention, being illustrated with the operator's hand in outline.

My invention may be more fully understood by direct reference to the illustration of a preferred form:

I prefer to make the body of the device unitary, and therefore it may be made of wood, metal, plastics or other compositions that will be readily apparent to those skilled in the art.

35 The hand grip 1 of the device is preferably provided with ridges 2 which fit between the fingers and thus prevent the weapon from moving out of the hand when a blow is struck therewith. I prefer to form my weapon double-ended so that it projects from both sides of the hand, and I prefer to make both sides alike, although this is not necessary to the carrying out of my invention as the ends may be modified within the scope of the appended claims. However, I prefer to terminate the weapon at each end thereof 40 in a rounded striking end 3 in order that the blows struck by the club will not unduly cut or lacerate the body of the person hit.

Between the rounded striking ends 3 and the 50 hand grip 1 of the device, I prefer to form the contour of the device in a series of angularly disposed faces 4, and so arranged with relation to each other that they will form a succession of peripheral sharp ridges 5, and the main purpose 55 of these sharp ridges is to prevent an opponent from grasping the projecting ends of the weapon and wrenching it out of the user's hand.

In order to still further prevent loss of the weapon, I prefer to insert into the terminals of the 60 device, extending from the faces thereof, pins 6,

preferably terminating in sharp points so that if the ends are grasped by an opponent, a slight twist of the weapon will so injure the grasping hand that the weapon will be released. However, in order that the sharp points of the pins 5 6 may not injure the person struck, I may prefer to form the faces 4 with a relatively deep concavity so that the ends of pins 6 do not project beyond a line drawn from the inner end of the faces to the outer end of the faces. 10

While I have described the formation of the projecting ends of the device as having a certain arrangement of points, ridges and faces, it is obvious that other arrangements will be fully as satisfactory to prevent the weapon from being 15 wrested from the grip of the user.

The device has been found highly satisfactory for use at close quarters in riots or in other peace disturbances where an ordinary night stick or policeman's billy is too long to handle satisfactorily, and where there is great danger of having the weapon wrenches from the hand of the peace officer using it. 20

I claim:

1. A police weapon comprising a substantially 25 cylindrical body having a ridged handle portion of a size to be readily grasped by the hand, and portions extending beyond the hand and terminating in rounded striking surfaces, and angular faces joining to form sharp edges between 30 the handle portion and said rounded striking surfaces.

2. A police weapon comprising a substantially cylindrical body having a ridged handle portion of a size to be readily grasped by the hand, and portions extending beyond the hand and terminating in rounded striking surfaces, and a plurality of sharp edges on the surface of said terminal portions between the handle portion and said rounded edges. 35

3. A police weapon comprising a substantially cylindrical body having a ridged handle portion of a size to be readily grasped by the hand, and portions extending beyond the hand and terminating in rounded striking surfaces, said terminal portions having adjacent concave faces formed therein to provide longitudinal sharp edges between said handle portion and said rounded surfaces. 40

4. A police weapon comprising a substantially 50 cylindrical body having a ridged handle portion of a size to be readily grasped by the hand, and portions extending beyond the hand and terminating in rounded striking surfaces, said terminal portions having adjacent concave faces 55 formed therein to provide longitudinal sharp edges between said handle portion and said rounded surfaces, and a plurality of sharp points extending from said concave faces.
